C. D. BONSALL,
END REINFORCEMENT FOR RAILWAY BOX CARS,
APPLICATION FILED APR. 15, 1919.

Patented Oct. 24, 1922.

UNITED STATES PATENT OFFICE.

CHARLES D. BONSALL, OF NEW KENSINGTON, PENNSYLVANIA, ASSIGNOR TO WALTER P. MURPHY, OF NEW YORK, N. Y.

END REINFORCEMENT FOR RAILWAY BOX CARS.

Application filed April 15, 1919. Serial No. 290,217.

To all whom it may concern:

Be it known that I, CHARLES D. BONSALL, a citizen of the United States, residing at New Kensington, in the county of Allegheny 5 and State of Pennsylvania, have invented certain new and useful Improvements in End Reinforcements for Railway Box Cars, of which the following is a specification.

My invention relates to a reinforcement 10 for the end walls of railway box cars of wood construction of the type employing a pair of upright metal reinforcing elements which are secured by suitable bracing or anchoring means to the roof framing and 15 under framing of the car. While the end wall of a railway car is liable to cargo thrusts at all points thereon, and is always subject to "weaving" stresses, the most destructive thrusts of the lading are likely to 20 be at or near the floor of the car where the heavier articles are usually placed. My invention seeks to take advantage of this circumstance for the purpose of economizing metal in the manufacture of the upright reinforcing members and minimizing the 25 weight of the reinforcing structure by forming said members so that they will be heaviest and strongest at the bottom and of gradual diminishing weight and strength toward the roof of the car. The invention contemplates making a pair of such reinforcing members from a single rectangular plate which is divided on a diagonal line and 30 each half of the plate pressed to a Z-shape 35 in cross section, the web of the Z-bar being widest at its lower end and tapered in width toward the top; the web, however, having a substantial width at the top so as to insure rigid anchorage to the bracing 40 frame that forms an integral part of the reinforcement and transmits the loads on the upright members to the side wall frame members of the car.

The invention is illustrated, in a preferred 45 embodiment, in the accompanying drawings, wherein—

Fig. 1 is an end view of the superstructure of a railway box car reinforced in accordance with the invention.

Fig. 2 is sectional plan on line 2--2 of Fig. 1.

Fig. 3 is a plan view of the upper portion of the car framing with the roof structure removed.

Fig. 4 is a vertical sectional view on line 55 4--4 of Fig. 1.

Fig. 5 is a diagram of the blank from which the two upright reinforcing members are manufactured, and

Fig. 6 is a fragmentary view, on a larger 60 scale of the severed blank for one of these members, the dotted lines indicating the lines on which the blank is bent to give the reinforcing member formed therefrom the desired cross sectional configuration. 65

Like characters of reference designate like parts in the several figures of the drawings.

Referring to the drawings, 10 indicates the end sheathing of the car, 11 the end lining, 12 the corner posts, 13 the end sill, 14 the end posts, 15 the diagonal braces, 16 the end plate and 17 the side plates. 70

Aligned with the end posts 14 on the outside of the car are a pair of metal reinforcing members 18 which are preferably formed by severing a rectangular blank 19 (Fig. 5) along the diagonal line 20 and bending each of the blanks 21 along the lines 22, 23 (Fig. 6) running substantially parallel to the respectively adjacent edges of the blank to give the member a Z-shape in cross section. The flanges 24, 25 of the Z-bars thus formed are of substantially uniform width for their entire length but the intervening web 26 is widest at the lower end of the bar and diminishes in width toward the top. The Z-bars are anchored to the end sill 13 by means of bolts 27 and by short angles 28 riveted to the outstanding 90 webs 26 of the Z-bars and secured to the sill by bolts 29. If desired the flanges 24 of the Z-bar may be fastened at intervals to the end posts 14 by bolts 30. 80

The upper ends of the Z-bars are secured 95 to an angular member 31 fastened by bolts 32 to the inside of the end plate 16. Any suitable form of bracing structure may be employed for distributing the stresses on the angular member 31 to the side walls of the 100 car and for bracing the roof framing of the car as against weaving strains. I have shown a pair of diagonal intersecting braces 33 fastened at one pair of extremities to the angular member 31 and at the other to an 105 angular members 34 secured by bolts 35 to the side plates 17, the braces 33 being preferably secured together at their intersection by a

2
gusset plate 36. The reinforcing members 18 preferably extend considerably above the angular member 31 and have their upper ends secured by bolts 37 to the end plate 16 as shown in Fig. 4.

I claim:

1. In combination with the wooden end wall of a railway box car, a metal reinforcing structure for the end of the car comprising a pair of upright members Z-shaped in cross section, the aggregate transverse dimension of the web and flanges of each of which is greatest near the floor of the car and diminishes toward the roof.
- 10 2. In combination with the wooden end wall of a railway box car, of a metal reinforcing structure for the end of the car comprising a pair of upright members Z-shaped in cross section, the width of the outward standing web of each of which is greatest near the floor of the car and diminishes toward the roof.
- 15 3. In combination with the wooden end wall of a railway box car, a metal reinforcing structure for the end of the car comprising a pair of upright members Z-shaped in cross section from end to end with their outstanding webs widest near the floor of the car and diminishing toward the roof and the flanges of said members being of substantially uniform width.
- 20 4. In combination with the wooden end wall, side walls and end sill of a railway box car, a bracing structure arranged with- 50
- 25 standing web of each of which is greatest near the floor of the car and diminishes toward the roof.
- 30 5. In combination with the wooden end wall, side walls and end sill of a railway box car, a bracing structure arranged with- 55
- 35 standing web of each of which is greatest near the floor of the car and diminishes toward the roof.
- 40 6. In combination with the wooden end wall, side walls and end sill of a railway box car, a bracing structure arranged with- 60
- 45 standing web of each of which is greatest near the floor of the car and diminishes toward the roof.
- 50 7. In combination with the wooden end wall, side walls and end sill of a railway box car, a bracing structure arranged with- 65
- 55 standing web of each of which is greatest near the floor of the car and diminishes toward the roof.
- 60 8. In combination with the wooden end wall, side walls and end sill of a railway box car, a bracing structure arranged with- 65
- 65 standing web of each of which is greatest near the floor of the car and diminishes toward the roof.

the end wall and side walls, and a pair of pressed steel, upright members Z-shaped in cross section connected to the end sill at the bottom and at the top to said bracing structure and formed so as to be heaviest 40 and strongest at their lower ends and of diminishing weight and strength toward the top.

5. In combination with the wooden end wall, side walls and end sill of a railway 45 box car, a bracing structure arranged with- in the car connecting the upper portion of the end walls and side walls, and a pair of pressed steel, upright members Z-shaped in cross section connected to the end sill at 50 the bottom and at the top to said bracing structure, and having outstanding webs which are widest at the bottom and diminish in width toward the top.

6. In combination with the wooden end 55 wall of a railway box car, a metal reinforcing structure for the end of the car comprising a pair of pressed metal members, Z-shaped in cross-section and made in each case from a blank in which one longitudinal 60 edge of the blank is oblique to the other, each of said members extending from a point adjacent the floor of the car to the roof and formed with an outstanding web of greater width at the bottom than at the 65 top and with flanges of substantially uniform width throughout projecting from opposite faces of said web.

CHARLES D. BONSALL.

Certificate of Correction.

It is hereby certified that in Letters Patent No. 1,432,956, granted October 24, 1922, upon the application of Charles D. Bonsall, of New Kensington, Pennsylvania, for an improvement in "End Reinforcements for Railway Box Cars," an error appears in the printed specification requiring correction as follows: Page 1, line 80, for the reference numeral "21" read 22; and that the said Letters Patent should be read with this correction therein that the same may conform to the record of the case in the Patent Office.

Signed and sealed this 28th day of November, A. D., 1922.

[SEAL.]

KARL FENNING,

Acting Commissioner of Patents.
